UNITED STATES PATENT OFFICE.

LARNED E. MEACHAM, OF CHICAGO, ILLINOIS.

COMPOUND PAPER WRITING-SHEET.

No. 797,303.

Specification of Letters Patent.

Patented Aug. 15, 1905.

Application filed December 26, 1903. Serial No. 186,566.

To all whom it may concern:

Be it known that I, LARNED E. MEACHAM, of Chicago, in the county of Cook and State of Illinois, have invented certain new and useful Improvements in Compound Writing-Paper Sheets; and I hereby declare that the following is a full, clear, and exact description thereof, reference being had to the accompanying drawings, which form part of this specification.

My invention has for its primary object to produce as an article of manufacture a compound writing-sheet that will fulfil the requirements of business use and that embodies structural features which facilitate rapidity and accuracy in its manipulation in business uses.

It is commonly known that in one of the most usual systems of business correspondence and other business transactions writings are prepared by type-writing, a carbon-copy of the writing being simultaneously made by the usual manifolding process. As now commonly practiced, however, the "original" sheet and the "copy-sheet" are independent and separate pieces of paper. In writing these are placed together by the manipulator of the type-writer with a sheet of carbon-paper interposed therebetween and are arranged in proper register. These sheets then have to be carefully held while they are run into the machine to prevent them losing their proper alinement, and so causing the words to be printed awry on one or the other thereof, to the detriment of the appearance of one of the copies. It is also the common experience of persons engaged in the operation of type-writing machines that much annoyance is caused in the process of manifolding by the frequent "creeping" or shifting of the under or copy sheet from its first position of proper alinement with the upper or original sheet, caused by unequal frictional contact between the said sheets and the working parts of the type-writing machine. Furthermore, when the separate paper sheets are removed from the machine they lose their alinement in handling, so that should interlineations or changes have to be made in the written matter such changes have to be entered separately in the original and the copy, as it is practically impossible to reinsert the paper sheets in the same relative positions they first occupied. It is with a view to providing an article of paper manufacture which will obviate all of these difficulties and be conducive to rapidity and

accuracy of work that my compound writing-sheet is designed.

In the drawings, wherein I have illustrated an embodiment thereof which I find to be practical and advantageous in many respects, Figure 1 is a plan view of a compound sheet. Fig. 2 is a plan view of the copy-sheet detached. Fig. 3 is a section on line 3 3 of Fig. 1. Fig. 4 is a side elevation of the compound sheet.

It will be understood that in these drawings the features sought to be particularly illustrated are grossly exaggerated.

Referring now to said drawings, 5 indicates an original writing-paper sheet upon which the original imprint of the inscription is taken. The said sheet may be made of any quality of paper, preferably, for business uses, of a relatively high grade.

6 indicates a copy sheet, preferably substantially of the same configuration and size as the original sheet 5. Said copy-sheet 6 may be, and preferably is, made of relatively low-grade paper and relatively thinner than the original sheet. It may further be differentiated from the original sheet in color or texture. The copy-sheet 6 is preferably perforated, as at 7, near its top edge to receive the pins of the ordinary standard filing-binders, and so facilitate filing. Original sheet 5 is superposed upon the copy-sheet 6 and the two simple sheets are connected together below their corresponding upper edges to constitute my "compound" sheet. In practice I prefer to effect such connection by means of paste dots 8 8, the paste being preferably of such a nature as to have comparatively slight tenacity, so that it may be easily broken away from the paper to which it adheres, and the dots placed at relatively wide intervals to allow the paper sheets to be separated readily and without mutilation. In practice I have found that this may be easily accomplished by a proper selection of the adhesive material.

In effecting the union of the original and copy sheets I prefer to so relatively place the original and copy sheets that the upper edge of one is somewhat below the edge of the other sheet, as best illustrated in Figs. 1 and 4. If then, as I prefer, the two sheets are of the same absolute length, the lower edge of the copy-sheet 6 projects somewhat below the lower edge of the original sheet, as illustrated.

In the use of the article constructed as described the carbon-sheet commonly employed

is inserted between the original and copy sheets of the compound sheet, the points of adhesion of the original and copy sheets forming, in effect, abutments to properly position the carbon-sheet. Now it will be apparent that the compound sheet with the carbon in place may be inserted in the type-writer as readily as a single sheet could, no care being necessary as regards alinement of the sheets relative to each other. It will also be noted that the construction illustrated is such as to facilitate the insertion of the paper sheet into the type-writer by virtue of the offset relation of the top edges of the original and copy sheets. The effect obtained is that of an incline or wedge, the single thickness of the original sheet entering the machine in advance of the copy-sheet and the additional thickness caused by the carbon-sheet following after the upper edge of said copy-sheet.

When the paper is removed from the machine, it will be apparent that the carbon-paper may be left in place until after the letter is signed if it be desired to secure a facsimile of the signature of the sender upon the copy-sheet. It will also be apparent that should any changes or interlineations be made by pen or pencil they will thus be reproduced upon the copy-sheet, while any extensive changes or interlineations may be entered upon the type-writing machine, the attachment of the two sheets rendering it impossible for them to get out of register in their reinsertion into the machine, so that the interlineations will positively appear at the proper points upon the copy. When now the original and copy sheets are to be separated, they are torn apart. The projecting lower edge of the copy-sheet affords a convenient place for the fingers to grasp to separate the sheets. Disassociation of the sheets is readily accomplished when they are connected by the use of paste by the breaking of the paste itself from one or the

other of the sheets, so that both are preserved intact. The segregated copy-sheet appears as shown in Fig. 2.

The perforations 7 7 are useful in filing away the duplicate copies in the loose-leaf binders now usually employed.

While I have herein described and illustrated my invention as particularly applied to writing-sheets adapted for correspondence, it will be apparent that its principles might be applied to paper for the purpose of any writing where it is desired to make one or more copies. It will also be apparent that slight changes in the exact construction might be made without departing from the spirit and scope of my invention.

Having thus described my invention, what I claim, and desire to secure by Letters Patent of the United States, is—

1. As an article of manufacture a compound writing-paper sheet comprising an "original" sheet of paper suitable for transmission in commercial correspondence; a "copy-sheet" of paper, said sheets being superposed one upon the other with their upper edges out of register, and bodies of an adhesive substance connecting said sheets below their upper edges at points relatively remote from the median line of the sheet intersecting said edges.

2. As an article of manufacture a compound writing-sheet comprising two independent paper sheets of substantially equal size superposed one upon the other with their horizontal edges out of register and connected together at their upper ends in a line below their uppermost edges.

In testimony that I claim the foregoing as my own I affix my signature in presence of two witnesses.

LARNED E. MEACHAM.
In presence of—

MARY F. ALLEN,
GEO. T. MAY, Jr.
